UNITED STATES PATENT OFFICE.

ARTHUR L. BETTS AND PAUL S. SHIELD, OF CINCINNATI, OHIO, ASSIGNEES TO
AUGUSTINE DAVIS, JR., OF COVINGTON, KENTUCKY.

BUMPER FOR TANK-VEHICLES.

1,366,353.

Specification of Letters Patent. Patented Jan. 25, 1921.

Application filed August 4, 1920. Serial No. 401,187.

To all whom it may concern:

Be it known that we, ARTHUR L. BETTS and PAUL S. SHIELD, citizens of the United States, and residents of Cincinnati, in the 5 county of Hamilton and State of Ohio, have invented a new and useful Bumper for Tank-Vehicles, of which the following is a specification.

The invention has reference to tank vehicles, such as oil tank wagons and trucks, in 10 which the contents of the tank (usually compartmented) are dispensed from faucets at the rear. To guard against injury to these faucets and the loss and danger resulting 15 from escape of oil or gasoline in event of their breakage by rear collision, it is advisable to protect them with a bumper; but this makes it difficult to place the buckets on and off the hooks on the faucets, and there has 20 consequently been dissatisfaction with the use of such bumpers, causing them in some quarters to be rejected. To meet this situation special bucket-guiding hooks have been provided, as disclosed in Patents No. 1,330,623 25 of February 10, 1920, and No. 1,332,614 of March 2, 1920. The present invention aims to overcome the difficulty in a still simpler and more satisfactory manner, while preserving the full advantage of the bumper; 30 and this is accomplished by constructing the bumper so that it is normally rigid and can be readily lifted up to clear the faucets for application and removal of the buckets.

The preferred embodiment of the construction will now be briefly described, reference being had to the accompanying drawings, wherein:

Figure 1 is a plan view of the rear portion of an oil tank vehicle, illustrating the 40 invention;

Fig. 2 is a side elevation, showing in dotted lines the bumper-bar raised and swung back out of the way;

Fig. 3 is a fragmentary plan view of the 45 bumper on a larger scale; and

Fig. 4 is a sectional side elevation taken on the line 4—4 of Fig. 3.

The drawing illustrates the tank 1 of an oil tank truck, 2 are side sills representing a 50 supporting frame, 3 the bucket-box at the rear end of the tank, and 4 the faucets, below the bucket-box, on the ends of pipes leading from the compartments of the tanks.

The faucets are of usual construction, and 55 have hooks 5 at the back on which to hang

the handles of buckets, in which the oil and gasoline are carried to the customers' storage tanks. It is ordinarily an awkward matter to get the handles on and off these hooks, when the faucets and bucket-box are protected by a rear bumper.

The bumper of this invention is designated generally 6. It may be said to be composed of a fixed part, comprising side members 7, and a movable part, consisting 65 of a bumper-bar 8.

The side members 7 are bolted to the rear ends of side sills 2 of the mounting or of the chassis, and are offset laterally outward at their intermediate inclined portions 10, and 70 have straight, parallel rear portions 11. The side members and the bar 8 are advantageously made of channels, and the ends 12 of the bar preferably extend beyond the portions 11 and are curved forwardly; but it 75 will be understood that these and other details may be varied.

Two plates or members 13 are fixed to the bumper-bar, so as to project forwardly at points somewhat inward of the end portions 80 12, as by bending the forward parts 14 of the plates outward and riveting them to the back of the channel. These plates normally extend alongside the rear portions 11 of the side members, and in their forward portions 85 are longitudinal, closed-end slots 15. Said slots receive pivot studs 16 which project outward from the portions 11 of the side members, slotted pivotal connections being thus afforded between the bumper-bar and 90 the side members, permitting the bar to be lifted up so as to expose the faucets and their hooks 5; the pivots being properly located for this purpose.

The bumper-bar is normally confined 95 against vertical movement, upward or downward, by a lock, which as illustrated herein may be termed a rigid socket or double jaw lock. A simple form comprises plates 17 riveted to the under sides of the members 7 100 and overlapping the bumper-bar at the bottom, and another pair of plates 18 riveted to the side members at the top and overlapping the top of the bar. The rear ends of the latter jaw members are desirably curved 105 and rolled as shown at 19, for strength and to facilitate lifting and replacement of the bar.

The bumper-bar can thus be pulled out from the confinement of the lock, prepara- 110

tory to being swung upward out of the way. It is normally restrained, however, by springs 20, which hold the bar to its seat, against the ends of the side members and 5 within the jaws of the lock. Said springs may be hooked at one end to eye-bolts 21 on the bumper-bar, and at the other end to the pivots 16, between the heads thereof and nuts 22. The fact of the bumper bar being 10 in abutting relation to the side members saves the pivots from shock in event of collision.

What is claimed as new is:

1. In a tank vehicle, the combination with 15 the frame and rear faucets, of a bumper on the rear end of the frame protecting the faucets, said bumper comprising side members extending rearward from the frame, a lift-up bumper-bar movably connected to the 20 side members, and means for locking the bar to said side members.

2. In a tank vehicle having faucets at the rear end, a bumper protecting said faucets comprising side members extending 25 rearward from the vehicle and having their rear portions offset laterally outward, a bumper-bar having members projecting forward and pivoted to said offset rear portions of the side members, and means for 30 locking the bumper-bar to the side members.

3. In a bumper of the kind described, the combination of side members, and a bumper-bar pivotally connected to the side members 35 so as to swing up, the bumper-bar being in abutting relation to the side members in its lowered position so that the pivotal joints are saved from the shock of collision.

4. In a bumper of the kind described, the 40 combination of side members, a bumper-bar having loose pivotal connections with said side members so that the bar can be swung up, the bumper-bar in its lowered position abutting against the side members, and 45 spring means holding the bar tight to the side members.

5. In a bumper of the kind described, the combination of side members, and a bumper-bar having members overlapping the side 50 members and loosely pivoted thereto so that the bar can be swung up, the bar being in abutting relation to the ends of the side members in the lowered position.

6. In a bumper of the kind described, the 55 combination of side members, a bumper-bar

having loose pivotal connections with said side members so that the bar can be swung up, the bumper-bar in its lowered position being in abutting relation to the side members, and a lock for the bumper-bar.

60

7. In a tank vehicle having faucets at the rear end, a bumper protecting said faucets, comprising side members, and a bumper-bar having slotted pivotal connections with the side members enabling it to be pulled out 65 and swung up to clear the faucets, together with a lock between the bumper-bar and side members disengaged by pulling out the bumper-bar, and springs for maintaining the parts in locked relation.

70

8. A bumper of the kind described comprising side members, and a movable part comprising a bumper-bar having slotted pivotal connections with the side members enabling it to be pulled out and swung up, together 75 with upper and lower jaws on one of the parts normally confining the bar against vertical movement while permitting disengagement, and springs opposing such disengagement.

80

9. A bumper of the kind described comprising side members having pivots thereon, and a movable part comprising a bumper-bar having slotted plates extending therefrom alongside the side members in engagement with the pivots, together with upper and lower jaws on one of the parts receiving the other part, and springs normally holding the bar seated.

85

10. A bumper of the kind described comprising side members having pivots thereon, and a movable part comprising a bumper-bar having slotted plates extending therefrom alongside the side members in engagement with the pivots, together with upper 90 and lower jaws on one of the parts receiving the other part, and springs connected to the bar and to said pivots.

95

11. A bumper of the kind described, comprising side members, a bumper bar having 100 slotted pivotal connections with the side members enabling it to be pulled out and swung up, jaw members fixed to the side members and overlapping the top and bottom of the bumper-bar, and springs arranged to draw the bumper-bar against the side members between said jaw members.
